US00D553971S

(12) **United States Design Patent** (10) **Patent No.:** **US D553,971 S**
Krueger (45) **Date of Patent:** **** Oct. 30, 2007**

(54) **PIPE AND TUBE SUPPORT**(75) Inventor: **Carey Krueger**, Newton, NJ (US)(73) Assignee: **Behringer Corporation**, Branchville, NJ (US)(**) Term: **14 Years**(21) Appl. No.: **29/222,603**(22) Filed: **Jan. 31, 2005**(51) **LOC (8) Cl. .... 08-08**(52) **U.S. Cl. .... D8/396**(58) **Field of Classification Search** ..... D8/354-356, D8/371, 394-396, 376, 382; 24/16 R, 279; 248/49, 62, 74.1-74.4, 73

Primary Examiner—Louis S. Zarfas*Assistant Examiner*—John Windmuller(74) *Attorney, Agent, or Firm*—McCarter & English, LLP(57) **CLAIM**

The ornamental design for a pipe and tube support, as shown and described.

DESCRIPTION

FIG. 1 is a front perspective view of a pipe and tube support showing my new design;

FIG. 2 is a front elevational view thereof;

FIG. 3 is a right side elevational view thereof;

FIG. 4 is a left side elevational view thereof;

FIG. 5 is a bottom plan view thereof; and,

FIG. 6 is a top plan view thereof.
